UNITED STATES PATENT OFFICE.

JOHN B. STAMOUR, OF PHILADELPHIA, PENNSYLVANIA, ASSIGNOR TO THOMAS CUNNINGHAM, LUCIAN BROWN, GEORGE BROWN, HORATIO B. LINCOLN, FRANK P. PENDLETON, AND HERMAN E. CUNNINGHAM, ALL OF SAME PLACE.

LOOM-TEMPLE.

SPECIFICATION forming part of Letters Patent No. 274,404, dated March 20, 1883.

Application filed September 18, 1882. (No model.)

To all whom it may concern:

Be it known that I, JOHN B. STAMOUR, a subject of the Queen of Great Britain and Ireland, and a resident of Philadelphia, Pennsylvania, have invented certain Improvements in Loom-Temples, of which the following is a specification.

My invention relates to certain improvements in that class of loom-temples which are hung to rods on the inner side of the breast-beam, the objects of my invention being to insure perfect freedom in the movement of the roller-carrier, to readily lock the latter to or permit it to be turned on the rod which carries it, and to provide for the ready insertion of the toothed roller into or the removal of the same from the roller-carrier.

In the accompanying drawings, Figure 1, Sheet 1, is a plan view, partly in section, of my improved loom-temple, the cover of the roller-carrier being thrown back so as to expose the toothed roller. Fig. 2, Sheet 2, is a section on the line 1 2, Fig. 1, the cover of the roller-carrier being closed. Fig. 3 is a front view of the temple, partly in section, and looking in the direction of the arrow, Fig. 2. Figs. 4 and 5 are perspective views of the supporting-brackets and spring-boxes for the opposite ends of the yielding rod of the temple. Fig. 6 is a longitudinal section of the toothed roller and carrier, and Fig. 7, Sheet 1, a view of the same with the roller detached from the carrier.

A represents part of the breast-beam of a loom, to the inner side of which is secured a bracket, B, on which is a projecting wing, a, and to the latter is secured by means of a bolt, b, a box, D, the wing of the bracket being slotted, so as to permit the adjustment of the box D toward or from the breast-beam, said box being guided by ribs d on the opposite edges of the wing a, as shown in Figs. 3 and 4.

Within the box D is a spring, E, bearing upon a rod, F, which projects laterally into and partly through the box D, and is retained therein partly by a pin, f, and partly by a block, g, secured to the rod, and grooved for adaptation to ribs h on the box. The opposite end

of the rod F is adapted to a box, D', containing a spring, E', and carried by a bracket, B', on the breast-beam, the attachments at both ends of the rod being exactly similar, except that the block g is used only in connection with the box D. By thus combining the brackets B B' with movable boxes D D', containing springs, against which bear the ends of the rod F, said rod can be readily adjusted to any desired distance from the inner side of the breast-beam, and is at liberty to move freely at both ends from and toward the breast-beam under control of the springs E E'.

To the rod F is loosely hung the roller-carrier G of the temple, said roller-carrier comprising the trough m, hinged cover n, plate p, and guide-plate s, the latter having the lugs s', through which the rod F passes.

To the rod F is secured a block, J, against which the lathe of the loom strikes in beating up, so as to drive the rod F toward the breast-beam, the springs E E' restoring said rod to its original position as the lathe is retracted. The block J also serves the additional purpose of maintaining the roller-carrier in its proper horizontal position on the rod, the guide-plate s bearing on the top of the block, as shown in Fig. 2. By moving the roller-carrier on the rod F in the direction of the arrow, Fig. 1, however, until the plate s is clear of the block J, the carrier can be turned up, as shown by dotted lines in Fig. 2—an operation which has sometimes to be resorted to when it is desired to gain access to the edge of the fabric which is being woven.

The toothed roller which I prefer to use comprises a series of independent toothed rings, z, a series of filling-pieces, z', and end blocks, z'', the whole being confined to a spindle, t, by a nut, v. The ends w of the trough m of the roller-carrier are slotted, so that the roller and its spindle can be readily slipped into place or removed in a vertical direction, as shown in Figs. 6 and 7, the spindle being confined longitudinally to the outer end of the trough by the head x of said spindle and one of the end blocks of the roller. The nut v may also be

large enough to assist in the endwise retention of the roller; but this is not essential. The head x of the spindle t , being rectangular and fitting snugly in the slotted end of the trough, 5 serves to prevent the spindle t from turning, and thereby loosening the nut v .

The cover n , when depressed, is locked in position by means of a turn-buckle, such as shown in Figs. 1 and 2.

10 I claim as my invention—

1. The combination of the rod F and the roller-carrier thereon with the boxes $D D'$, the springs $E E'$, and the brackets $B B'$, adapted to be secured to the inner side of the breast-15 beam A , as set forth.

2. The combination of the rod F , the roller-carrier thereon, the boxes $D D'$, the springs $E E'$, the brackets $B B'$, and the block g , secured to the rod F , and adapted to engage with 2c the box D , as set forth.

3. The combination of the rod F , having a block, J , with the roller-carrier pivoted to the rod, so as to be free to turn thereon, said carrier being also free to be moved laterally into or out of engagement with the block J , as set 25 forth.

4. The combination of the trough m of the roller-carrier, having slotted ends, with the composite toothed roller $z z' z^2$, having a spindle, t , with head x and nut v , as set forth. 30

In testimony whereof I have signed my name to this specification in the presence of two subscribing witnesses.

JOHN B. STAMOUR.
